UNITED STATES PATENT OFFICE.

EMIL VOLK, OF GEMMELL, MINNESOTA.

COMBINATION-LOCK.

1,304,633.

Specification of Letters Patent. Patented May 27, 1919.

Application filed January 3, 1917. Serial No. 140,343.

To all whom it may concern:

Be it known that I, EMIL VOLK, a citizen of the United States, resident of Gemmell, county of Beltrami, and State of Minnesota, have invented certain new and useful Improvements in Combination-Locks, of which the following is a specification.

This invention relates to improvements in locks, particularly of the type adapted to be used in connection with trunks and like receptacles, the lock being of the permutative character.

The principal object of the invention is to provide a lock which is comprised of few and simple parts readily applied to containers in which the upper or cover element is engaged with the main or body element, the lock occupying but small space and operable by manipulating exterior elements without a key or extraneous appliance.

These and other objects are attained by the novel construction and combination of parts hereafter described and shown in the accompanying drawings, forming a material part of this specification, and in which:—

Fig. 1 is a perspective view showing a fragment of the container and indicating the application of the lock thereto.

Fig. 2 is a vertical sectional view taken through the center line of the lock and container.

Fig. 3 is a sectional view taken on line 3—3 of Fig. 2.

Fig. 4 is a rear plan view of the hingedly movable part of the lock, parts being broken away to disclose the interior.

Fig. 5 is a perspective view of the fixed element of the lock, and

Fig. 6 is a front plan view showing a modified form of lock operating means.

In Fig. 1, which shows the application of the lock, the main or body portion of the container is indicated by the numeral 10, and the upper or cover portion by 12.

Attached to the fixed body portion 10 is a plate 14 secured by the rivets 15, the upper edge of the plate being formed into a hinge 16 with which is engaged a leaf 17, the same being formed with an enlarged circular plate 18 having downwardly turned edges 19 forming in effect a concave casing.

Disposed on the cover element 12 of the container is a rectangular plate 20 held rigidly in position by the rivets or bolts 21, the plate having a rigid upstanding flat pro-

jection 22 of such length as to be entirely covered by the casing 18, when the lock is in a closed position, and being formed with a series of steps 23, 24, and 25, each of which 60 is under-cut for purposes which will be later on apparent.

Rigidly attached to the plate 18 is a cylindrical casing 28 having an integral cover 29 through which is formed an elongated 65 rectangular aperture 30 receptive of the projection 22 when the lock is in an engaged position.

Formed on the exterior of the plate 18 is a graduated dial 32, and passing through 70 an opening in the center of the plate is a hollow sleeve 34, formed with a flanged circular disk 35 having a knurled or corrugated edge by which it may be rotated, the lower end of the sleeve 34 being rigidly engaged 75 with a tumbler disk 36 containing a single short lateral recess 37, formed radially, the disk being engageable with the outermost step 25 of the projection 22, the position of the disk being indicated by the numerals 80 38 placed on the outer surface of the rotatable disk 35.

Similarly, a second sleeve 40, is formed with a disk 41 overlying the disk 35 having a corrugated edge and provided on its upper surface with a series of numerals 42, the lower end of the sleeve 40 being rigidly engaged with the tumbler disk 43 containing a single slot 44 engageable with the step 24 of the projection 22. 90

Within the inner sleeve 40 is a post or spindle 45, its outer extending end being formed with a disk 46 having a corrugated edge and a plurality of numerals 47 disposed on its surface near its periphery; the lower end of the post 45 is rigidly engaged with a third tumbler disk 47 containing a slot 48 engageable with the lowermost step 23 in the projection 22. 95

Thus when the several openings 37, 44, 100 and 48 are in alignment and registering with the projection 22, the lock plate 17 may be turned downward upon its hinge 16 permitting the container to be opened.

Upon turning the plate 17 upward when 105 the openings are in register, the lock is placed in an operative position and upon turning any or all of the several disks 46, 41, and 35, the corresponding lower disks 36, 43, and 47 become engaged with the steps 110 23, 24, and 25, securing the two parts of the

lock together by rotating the outer numbered disks in an obvious manner with relation to the numerals on the several dials, the corresponding notches or recesses in the 5 lower disks may be readily manipulated.

In Fig. 6 a similar arrangement of locking disks is employed, together with the sleeves and inner stud. In this case the outer sleeve 34 is engaged with an index 10 hand 50, the second disk 43 being similarly engaged with the index 51, while the post 45 may be operated by the index 52, so that by turning the hands to a known position the locking disks may be rotated and moved 15 into any desired position, the interior of the lock being as before described.

Having thus described my invention, what I claim as new, and desire to secure by Letters Patent, is:—

20 In a combination lock of the character described, the combination with a container having a body portion and a hinged cover, of a plate secured to said hinged cover, a rigidly upstanding flat projection formed 25 with said plate and constituting a ward element, a casing covering said element entirely

when the lock is in its closed position, a plurality of recessed steps formed upon one edge of said element, a hollow sleeve in the center of the plate, a flanged circular disk, 30 having a knurled edge, formed with said sleeve, a slotted tumbler disk rigidly engaging the lower end of said sleeve, a second sleeve, a slotted tumbler disk rigidly engaging with said second sleeve, a spindle within 35 said second sleeve, a third tumbler disk, slotted, and rigidly engaging the lower end of said spindle, the slots in said tumbler disks being adapted to be engaged by the respective steps of said ward element, and 40 a plate on said body to which said hinged lock plate is secured for allowing a turning down when the tumblers with their slots are in alinement and register with said ward element, and said hinged lock plate being 45 further adapted to be turned up for allowing a locking of the container by the rotation of the tumbler disks for engagement with the steps of said ward element.

In testimony whereof I have affixed my 50 signature this 16th day of November, 1916.

EMIL VOLK.
